DESIGN FOR A CHARCOAL GRILL

Henry E. Roedter, Cincinnati, Ohio

Application August 19, 1947, Serial No. 140,951

Term of patent 14 years

(Cl. 81—10)

To all whom it may concern:

Be it known that I, Henry E. Roedter, a citizen of the United States, residing at Cincinnati, in the county of Hamilton and State of Ohio, have invented a new, original, and ornamental Design for a Charcoal Grill, of which the following is a specification, reference being had therein to the accompanying drawing, forming a part thereof.

Figure 1 is a perspective view of a charcoal grill, showing my new design.

Figure 2 is a top plan view of the grill shown in Figure 1.

Figure 3 is an end view of the grill shown in Figure 1.

Figure 4 is a fragmentary side view thereof with the handle broken away for convenience of illustration.

I claim:

The ornamental design for a charcoal grill, as shown.

HENRY E. ROEDTER.
